UNITED STATES PATENT OFFICE

GEORGE DE BOTHEZAT, OF NEW YORK, N. Y.

PULLEY-DRIVEN DISK FAN

Application filed June 30, 1928. Serial No. 289,534.

This invention relates to a rotary fan unit and more particularly to a fan unit having a fan of the disk pressure type.

The object of the invention is to provide a heavy duty, large diameter motor driven fan unit of convenient form and compact in overall dimension having a fan of the disk pressure type for forcing air in a generally axial direction and capable of developing high static pressure.

Further objects and advantages of the invention will be apparent from the following specification and drawing in which

Fig. 1 is a front elevation of a fan unit constructed in accordance with this invention.

Fig. 2 is a sectional elevation taken on line 2—2 of Fig. 1.

Fig. 3 is a development of the blades and disks of the fan taken on line 3—3 of Fig. 1, and

Fig. 4 is a development similar to Fig. 3 showing a modified form of fan blade construction.

As shown in the drawing, the whole unit is supported on an integral casting 10. The casting 10 is provided with a circular ring 11 in which the fan rotates, having a reinforcing flange 12. The flange 12 is provided at spaced intervals with extensions 13, 14, and 15 in which apertures 16 are provided for bolts or the like to fixedly attach and support the fan unit as a whole to a wall or other support with the ring 11 extending through a circular opening in the wall or other support. The elongated bearing 18 is spaced from, centered and rigidly attached to the ring 11 and flange 12 by extending arms 19, 20 and 21 leading from the extensions 13, 14 and 15. The extension 14 extends around the periphery of the flange 12 a substantial distance and has extending tangentially therefrom a flat top table 22 supported by arm 20 as clearly shown in Fig. 2. A source of power such as a motor 23 is fixed to table 22 having a pulley 24 driving a belt 25 which passes over pulley 26 fixed on the inner end of fan shaft 27 rotatable in bearing 18. In some cases it may be desirable to connect the motor 23 to the shaft 27 by

means of a chain or other device, the belt driving merely being shown by way of illustration.

The fan is of the disk pressure type having a hub 28 keyed or otherwise secured to the shaft 27. The hub 28 is flanged at 29 and has secured on either side by rivets 30 or like means the spaced boss flanges or disks 31 and 32. The aeroform fan blades 33 are spaced and secured between the bosses or disks 31 and 32 at their circumference and are of the same width throughout their length. The spaced angle irons 34 are riveted to the bosses or disks 32 by means of rivets 35 on one side edge of the blade is secured thereto by means of rivets 36. The opposite side edge of the blade is secured to boss or disk 31 by rivets 37 forming a rigid supporting means for the fan blades as clearly shown in Fig. 3.

In Fig. 4 is shown a modified means for securing the fan blades 33 to the boss or disk 31 which consists of a strip 38 secured at one end to the fan blades by rivets 39 and at its opposite end to the disk 31 by rivets 40. It will be noted that the blade angle n in the construction shown in Figs. 3 and 4 are identical.

The fan constructed in accordance with this invention is rigidly assembled and is especially adaptable for heavy duty wherein fans of large diameters are required. Furthermore it is not essential that the motor for operating the fan be located at the top of the unit as illustrated in the drawing, but may be placed in any position about the circumference of the fan.

Rotation of the fan of this invention creates a suction and the air is drawn to it in an axial direction. The air as it passes through the fan acquires a rotational motion as well as an axial motion leaving the fan in a smoother flow with substantially equal axial pressures throughout the length of the blades forcing the flow. Thus the flow from the fan is always free from eddy or cross current.

I claim:

1. A heavy duty fan unit comprising a disk pressure fan, a rotating motor therefor, the axes of the shaft and motor being out

100

- of line with each other, driving connections between the motor and the fan disposed at one side only of the plane of rotation of the fan, and a one-piece casting providing a support for said fan, said motor and said connections, said casting comprising a fan shaft bearing, a motor seat, and supporting arms for said bearing, said arms constituting the sole support of said bearing and all of them being disposed at the same side of the plane of rotation of the fan as said driving connections, said motor seat being interposed between said motor and the air currents generated by said fan.
2. In a fan unit the combination with a disk fan, of a one-piece casting comprising a ring member surrounding said disk fan, integral arms rigid with and extending from said ring member, an elongated shaft bearing supported by said arms, and a table supported along one edge by said ring and at right angles thereto along its under middle portion by one of said arms; a fan shaft in said bearing, a motor on said table; and means connecting said motor and said shaft for rotating said shaft and said fan, said arms constituting the sole support of the fan shaft bearing and all of them being disposed at one side only of the plane of rotation of the fan.
3. In a fan unit, a fan comprising a hub, two independent spaced disks secured to said hub, fan blades secured at their inner ends between said disks, said disks constituting the sole support of said blades, a one-piece casting comprising a supporting ring member surrounding said fan blades, arms extending from said ring member, a shaft bearing supported by said arms, and a supporting table extending from said ring member and supported by one of said arms, a motor on said table, a fan shaft in said bearing to which said hub is secured, and means connecting said shaft and said motor for rotating said fan, the supporting arms of the shaft bearing constituting its sole support, all of said arms being arranged at one side only of the plane of rotation of the fan, and said table shielding said motor from the air currents generated by said fan.
4. A heavy duty fan unit comprising a disk pressure fan, a motor therefor, the axes of the fan and the motor being parallel and out of line with each other, driving connections between said motor and said fan, the planes of movement of the fan and the connections being parallel, the motor being between said planes and outside the perimetral boundary of the fan, and a skeletonized one-piece casting providing a support for said fan, said motor and said connections, said casting constituted by a fan shaft bearing, a motor shelf, a protecting ring surrounding the fan, and connecting arms, all integral and rigid with each other, the connect-

ing arms constituting the sole support of the fan shaft bearing and all of them being disposed at one side only of the plane of rotation of the fan, and said motor shelf being interposed between said motor and the air currents generated by said fan.
